UNITED STATES PATENT OFFICE.

CHARLES E. LUCKE, OF NEW YORK, N. Y., ASSIGNEE TO GAS AND OIL COMBUSTION COMPANY, OF NEW YORK, N. Y., A CORPORATION OF DELAWARE.

METHOD OF BURNING LIQUID AND OTHER FUELS.

1,146,726.

Specification of Letters Patent. Patented July 13, 1915.

Application filed September 21, 1912. Serial No. 721,559.

To all whom it may concern:

Be it known that I, CHARLES E. LUCKE, a citizen of the United States, residing at New York city, in the county of New York and State of New York, have invented certain new and useful Improvements in Methods of Burning Liquid and other Fuels, fully described and represented in the following specification and the accompanying 10 drawings, forming a part of the same.

This invention relates to the combustion of liquid and other fuels and involves the mixing of the fuel in a finely divided state with a suitable combustion supporting gas 15 and then burning the mixture thus obtained.

The object of the invention is to provide an improved method of producing and burning explosive gaseous mixtures in such a way as to avoid all possibility of back- 20 flash or communication of the combustion bed to the source of supply, and to give a large range of control and adaptability; and the invention aims especially to provide an improved method of burning oils and other 25 liquid fuels, but in its broader aspect the invention is applicable to the burning of gaseous or other non-liquid fuels in a finely divided state suitable to be mixed with a combustion supporting gas to form a com- 30 bustible mixture having its fuel and combustion supporting constituents in proportions to form an explosive gaseous mixture, that is, one having the property of self-propagation of inflammation.

In the preferred manner of burning liquid fuel in accordance with the present invention, the liquid fuel and a combustion supporting gas are caused to flow against the face of a hot porous and permeable combustion supporting bed, whereby the fuel is vaporized by the heat adjacent to the face of the bed and the vaporized fuel then mixes adjacent to the face of the bed with the combustion supporting gas to form an explosive 45 mixture. The proportionate parts of fuel and combustible gas flowing against the face of the combustion bed should be such that the vaporized fuel and combustion supporting gas will form an explosive 50 mixture, and for best results the velocity with which the combustion supporting gas flows toward the face of the bed should be such that the mixture will move with a velocity greater than the 55 rate of propagation of inflammation through

the mixture, and will spread out over the face of the bed with decreasing velocity as explained in my application No. 721,557, filed September 21, 1912. Then, if the velocity of the mixture is sufficiently great it 60 may enter and advance a greater or less distance through the pores or passages of the bed before its velocity is reduced to the rate of propagation of inflammation, combustion taking place at the surface or zone 65 where equality between the rate of propagation of inflammation and the flow velocity of the gas is attained. Preferably, however, in practising the present invention the velocity of the impinging jet of combustion 70 supporting gas will be such that the velocity of the mixture will be reduced to the rate of propagation of inflammation at the impact face of the combustion bed so that the combustion will take place at the face of the 75 bed, as described in my said application No. 721,557 and in my application No. 721,558, filed September 21, 1912, thereby raising the face of the bed to a very high temperature so that it becomes highly incandescent and 80 radiates both heat and light to a high degree, as explained in my said applications. Whether the combustion is located at or beyond the impact face of the bed, the products of combustion may be permitted to escape from the combustion zone through the pores or passages of the bed. 85

When the combustion is to be located within the bed beyond the impact face, the bed should be of such a character, as explained in my said application No. 721,557, that as the explosive mixture advances from the impact face through the pores or passages of the bed it will be caused to spread out and advance in increasing volume and 90 with decreasing velocity, the bed being for this purpose formed with expanding or intercommunicating passages, or with passages which are both expanding and inter- 95 communicating. If, however, the combustion is to be localized at the impact face of the bed, the porous and permeable bed need only be of a character to provide for the escape therethrough of the products of combustion, and need not be of any considerable thickness, a comparatively thin perforate or porous diaphragm or plate being sufficient. For a lasting or permanent bed, a suitable refractory material, that is, one which will withstand the degree of heat to 100 105 110

which it is subjected, must be used. The surface of the bed should best be of such a character or have its surface particles or parts so shaped, as to promote proportionate passage of the mixture between the parts or particles and to prevent to the greatest degree the retention of a dead layer of gas on the side toward which the mixture is advancing. The degree of porosity and permeability should be such as to permit such free escape of the products of combustion that with a given supply of mixture the mixture will burn substantially in contact with all the physical surface over which the advancing stream spreads. A bed of pieces of refractory material of suitable size either loose or bonded meets the requirements well. Such a bed may be in the form of a thin plate or diaphragm or may be of any desired thickness. It is desirable, also, that the impact face of the bed be shaped according to the character and shape and arrangement of the jets or streams, caused to impinge thereon so as to secure the desired spreading of the mixture with reduction of its flow velocity to the rate of propagation of inflammation. Also, the bed may be of various shapes according to the purpose to which the invention is to be applied, and a single bed or a number of beds suitably grouped or arranged may be employed, the character and arrangement of the impinging jets or streams of fuel and combustion supporting gas corresponding to the arrangement and shape of the bed or beds.

The liquid fuel and combustion supporting gas may be supplied from a single nozzle or orifice, or the fuel and combustion supporting gas may be caused to flow from different nozzles or orifices in separate streams toward the face of the combustion bed, and for best results the separate streams should meet a short distance in advance of the face of the bed.

When a gaseous fuel or other non-liquid fuel in a finely divided state is to be burned, the fuel and combustion supporting gas will according to the present invention be caused to flow from separate nozzles, and the method will be the same as with a liquid fuel with the omission of the step of vaporizing the fuel, the fuel in all cases being mixed with a stream of unconfined combustion supporting gas and this mixing of the fuel and combustion supporting gas taking place preferably adjacent to and a short distance away from the surface of a combustion bed which, though not in all cases necessarily so, will, for securing the best results and all advantages of the invention, be a porous and permeable bed, as above pointed out.

It will be understood that by the term "explosive gaseous mixture" as used herein is meant a mixture of a suitable combus-

tion supporting gas, either oxygen alone or air or other oxygen containing gas, with combustible matter in a gaseous or finely divided state in proper proportions, that is, in proportions such that the mixture will have the property of self-propagation of inflammation. For producing the highest temperature, the oxygen should be undiluted and the mixture should contain oxygen and combustible matter in chemical combining proportions at the time of combustion, but there may be an excess of either combustible matter or the combustion supporting gas within the limits which determine the property of self propagation. The mixture may be varied in this respect according to the desired character of the products of combustion, that is, whether it is desired that the products shall be neutral, oxidizing or reducing. Also, the mixture may contain neutral gas, such as carbon dioxide, nitrogen or water vapor, so long as the amount of such neutral gas is not sufficient to make the mixture nonexplosive.

The accompanying drawings illustrate simple forms of apparatus adapted for carrying out my improved method.

In said drawings: Figure 1 shows a simple form of apparatus for burning oil or other liquid fuel in accordance with the method forming part of the present invention. Fig. 2, shows a modified arrangement of the nozzles. Fig. 3 is a view similar to Fig. 1 of a modified form of apparatus.

Referring first to Fig. 1, 10 represents a porous and permeable combustion bed. A jet of the liquid fuel is directed against an exposed face of the bed from a nozzle 11 to which the liquid may be supplied from any suitable source. As shown, the liquid is supplied from an elevated tank F through a pipe 12 provided with a valve 13 for controlling the amount of fuel discharged from the nozzle 11. A second nozzle 15 serves to direct a stream or jet of air or other combustion supporting gas against the impact face of the bed, the air being supplied from a tank A or other suitable source through a pipe 16 controlled by a valve 17. The nozzles 11 and 15 are best arranged as shown so as to cause the streams of fuel and combustion supporting gas to meet adjacent to and a short distance away from the impact face of the bed. When the apparatus is in use, assuming the combustion supporting bed to be sufficiently heated, the liquid fuel from the nozzle 11 when it strikes or comes close to the impact face of the bed will be vaporized, and the fuel vapor thus produced will mix adjacent to the face of the bed with the combustion supporting gas supplied from the nozzle 15.

The supply of fuel and combustion supporting gas should be regulated by the valves 13 and 17 so that they will be sup-

plied in proportions such that the vaporized fuel and combustion supporting gas mixing at the impact face of the bed will form an explosive mixture. The force of the impinging jet or stream of combustion supporting gas will cause the mixture formed at or near the impact face of the bed to spread out over the face of the bed. It is usually desirable that the velocity of the impinging stream or jet of combustion supporting gas shall be such as to cause the mixture produced adjacent to the impact face of the bed to move outward over the surface of the bed with an initial velocity greater than the rate of propagation of inflammation through the mixture. As the mixture spreads out its flow velocity will be rapidly reduced, and by properly controlling the velocity of the impinging jet of combustion supporting gas the initial velocity of the mixture may be adjusted so as to cause the flame cap or surface of combustion to locate at and close against the impact face of the bed. The greater part of the products of combustion will then pass away from the combustion zone or surface through the pores or passages of the bed and escape from a part of the surface of the bed other than the impact face. By sufficiently increasing the velocity of the impinging jet of combustion supporting gas and thereby the velocity with which the mixture moves from the place where it is produced, the flame cap or surface of combustion may, as before explained, be driven into the combustion bed and caused to locate in a zone a greater or less distance beyond the impact surface, assuming, of course, that the bed is of the proper character for localizing combustion beyond its impact face.

In order that the combustion zone or flame cap localized at the impact face of the bed may coincide more or less accurately with the impact face of the bed throughout the greatest possible or a considerable extent thereof, the impact face should be shaped according to the character of the jet. With a single solid jet of combustion supporting gas meeting one or more jets of the fuel adjacent to the impact face, and with the mixture impinging at substantially right angles against the face of the bed, an impact face of more or less circular concave shape, as shown in cross section by Fig. 1 answers the purpose well. This figure shows the combustion bed as formed of a mass of loose broken or other granular refractory material such as alundum or magnesite in a suitable container 20. If a comparatively weak mixture is to be burned, broken fire-brick will answer. With such a bed the products of combustion entering the bed may escape from the parts of the upper face surrounding or beyond the impact surface as indicated by the arrows, or might escape through

openings in the container. A bed formed of granular refractory material, either loose or bonded, meets the requirements for successfully carrying out the invention and is the best form of bed I know of at the present time; but, as already pointed out, it is not necessary when the combustion is to be localized at the impact face of the bed that the bed should be of such a character as to cause the expansion or lateral spreading of gases advancing through it.

In starting, the combustion bed may be heated in any suitable manner to a degree sufficient to vaporize the fuel from the nozzle 11. This may be accomplished in various ways, as by starting with a gaseous fuel in place of the liquid fuel, or by using a bed of burning coal or coke and maintaining this bed by the addition of fresh coal or coke or by adding loose pieces of refractory material to form a permanent bed as the coal or coke burns away. If an easily vaporized liquid fuel is used, the operation may be started by vaporizing the fuel at the start as it passes to or through the nozzle 11. This or a similar apparatus might, obviously, be used for burning a fuel gas or other suitable finely divided fuel by providing means for supplying such gas or other fuel to be discharged from the nozzle 11 to mix with the stream of combustion supporting gas from the nozzle 15 adjacent to and preferably a short distance away from the face of the bed. If a gaseous fuel is used, however, the apparatus should be made so as to secure a good mixing of the streams of fuel gas and combustion supporting gas, as for example by providing a plurality of fuel nozzles 11 arranged about the air nozzle 15 as shown in Fig. 2 for causing a plurality of jets of the fuel gas to join the air jet from different sides, or better by arranging a plurality of air nozzles about a central fuel gas nozzle.

In Fig. 3 there is shown a combustion bed having pores or passages through the bed of a uniform capacity or cross area from the impact face to the rear face of the bed, the bed being thus adapted to serve to carry away the products of combustion but not to cause a gradual decrease of velocity of gas flowing through them. This bed is adapted, therefore, only for combustion localized at the impact face of the bed. With a bed of this kind mounted as shown, the products of combustion would escape from the passages of the bed into the chamber 21 and pass therefrom through an outlet 22. In the apparatus shown in this figure, also, the fuel and the combustion supporting gas are discharged against the impact face of the bed from the same nozzle 15. The air or other combustion supporting gas is supplied as in Fig. 1 through pipe 16 from a tank A in which the pressure is maintained in any suit-

able manner. The pipe 12 from the fuel tank F instead of leading to a separate nozzle leads into the pipe 16, so that the oil or other liquid fuel entering the pipe 16 from the pipe 12 will be carried along by the air and discharged with the air from the nozzle 15. The fuel liquid will be more or less broken up into a spray in leaving the nozzle with the air, but unless a special atomizing or spray nozzle is provided the liquid fuel ~~may~~ still require to be vaporized before it will be in a sufficiently divided state to mix with the air or other combustion supporting gas to form an explosive gaseous mixture, so that in using an apparatus of this form for burning oil or other liquid fuel, and with the apparatus provided with a nozzle for delivering a solid or substantially solid jet, the mixture of the combustion supporting gas with the finely divided fuel, that is, in this case, vaporized fuel, to form the explosive gaseous mixture will take place adjacent to the impact face of the bed in the same manner as with an apparatus such as shown in Fig. 1.

Other ways of mixing vaporized liquid fuels or other finely divided fuel with the combustion supporting gas adjacent to a baffling surface will readily suggest themselves, and a combustion supporting bed or beds of other forms and construction from those shown may obviously be used in apparatus for practising my method. Examples of some other suitable beds are shown in my said applications, Nos. 721,557 and 721,558. It is to be understood, therefore, that various modifications of the apparatus shown may be used for practising the method of the present invention. Obviously any desired number of jets arranged in various ways and jets of various forms may be employed in connection with suitably arranged combustion beds of suitable character.

What is claimed is:

45. 1. The method of combustion which consists in forming an explosive gaseous mixture by mixing fuel in a finely divided state with a stream of combustion supporting gas moving unconfined with a velocity sufficient to cause the resulting mixture to move with a velocity greater than the rate of propagation of inflammation through the mixture, reducing the flow velocity of the mixture, and burning the mixture at the 50 zone or surface where the velocity equals the rate of propagation of inflammation.

55. 2. The method of combustion which consists in causing a stream of combustion supporting gas to flow unconfined against a baffling surface, mixing fuel in a finely divided state with the combustion supporting gas adjacent to the baffling surface in proportions to form an explosive gaseous mixture, and burning the mixture.

65. 3. The method of combustion which con-

sists in causing a stream of combustion supporting gas to flow unconfined against the face of a porous and permeable bed, forming an explosive gaseous mixture by mixing fuel in a finely divided state with the combustion supporting gas adjacent the impact 70 face of the bed in proportions to form an explosive gaseous mixture, the velocity of the stream of combustion supporting gas being such that the explosive mixture will flow with an initial velocity greater than the rate of propagation of inflammation through the mixture, burning the mixture where the velocity equals the rate of propagation of inflammation, and permitting the products 75 of combustion to escape through the pores or passageways of the bed.

4. The method of burning liquid fuel which consists in vaporizing the fuel and producing an explosive gaseous mixture by causing the fuel and combustion supporting gas to flow against a hot body in proportions such that the vaporized fuel and the combustion supporting gas will form an explosive mixture, the velocity of the combustion supporting gas being such that the explosive mixture will flow with a velocity greater than the rate of propagation of inflammation through the mixture, reducing the velocity of the mixture to the rate of propagation of inflammation, and burning the mixture where the velocity equals the rate of propagation of inflammation.

5. The method of burning liquid fuel which consists in vaporizing the fuel and producing an explosive gaseous mixture by causing the fuel and combustion supporting gas to flow against the face of a hot porous and permeable combustion bed in proportions such that the vaporized fuel and the combustion supporting gas will form an explosive mixture, the velocity of the impinging stream of combustion supporting gas being such that the mixture will move with an initial velocity greater than the rate of propagation of inflammation through the mixture and spread out over the face of the bed with decreasing velocity, burning the mixture, and permitting the products of combustion to escape through the pores or 100 passageways of the bed.

6. The method of burning fuel which consists in causing the fuel and combustion supporting gas to flow in separate unconfined converging streams toward the face of a porous and permeable combustion bed, whereby the fuel and combustion supporting gas will be caused to mix adjacent the impact face of the bed to form an explosive gaseous mixture, the velocity of the impinging stream of combustion supporting gas being such that the resulting explosive mixture will flow with an initial velocity greater than the rate of propagation of inflammation through the mixture, burning the mixture where the ve- 115 120 125 130

lacity equals the rate of propagation of inflammation, and permitting the products of combustion to escape through the pores or passages of the bed.

5. 7. The method of burning liquid fuel which consists in causing the fuel and combustion supporting gas to flow in separate streams toward the face of a hot porous and permeable combustion bed, whereby the fuel
10 will be vaporized and the fuel vapor will be caused to mix with the combustion supporting gas to form an explosive gaseous

mixture, burning the mixture at the impact face of the bed, and permitting the products of combustion to escape through the 15 pores or passages of the bed.

In testimony whereof I have hereunto set my hand in the presence of two subscribing witnesses.
